CLAIM

The ornamental design for a soundbar, as shown and described.

DESCRIPTION

FIG. 1 is a perspective view of a soundbar showing my new design;

FIG. 2 is a front elevational view thereof;

FIG. 3 is a top plan view thereof;

FIG. 4 is a left side elevational view thereof;

FIG. 5 is a rear elevational view thereof;

FIG. 6 is a right side view thereof; and,

FIG. 7 is a bottom plan view thereof.

The broken lines in FIGS. 2, 4, 5, 6 and 7 illustrate portions of the soundbar that form no part of the claimed design.
